Attorney, Agent, or Firm—Robert J. Doherty

[21] Appl. No.: **252,717**

CLAIM

[22] Filed: **Oct. 3, 1988**

The ornamental design for a diskette storage box for
normal insertion into unused disk drive space in com-
puter housing, as shown and described.

[52] U.S. Cl. **D14/114; D6/448;
D6/477**

DESCRIPTION

[58] **Field of Search** D14/100, 106, 114;
D6/422, 425, 427, 430, 432, 436, 437, 442, 449,
509-512; 312/198, 200, 204, 205, 201, 239, 242,
270, 299, 306; 211/90, 153; 248/678; 364/708

FIG. 1 is a top, front, right side perspective view of a
diskette storage box for normal insertion into unused
disk drive space in computer housing showing my new
design;
